JOHN M. MCCLATCHIE, OF NEW YORK, N. Y., ASSIGNOR TO THE BORDEN COMPANY, OF NEW YORK, N. Y., A CORPORATION OF NEW JERSEY

STEAM NOZZLE

Original application filed April 17, 1930, Serial No. 444,963. Divided and this application filed October 3, 1931. Serial No. 566,661.

This invention relates to an improvement in steam nozzles particularly intended for steaming or sterilizing the interior of milk-cans or other like hollow containers. This 5 application is a division of my co-pending application Serial No. 444,963, filed April 17, 1930.

The object of the invention is to provide an improved steam nozzle, of a construction enabling it to be inserted within a milk-can or other like container for the purpose of injecting steam therein to sterilize the can, which will direct steam free from condensate against the inner surfaces of the can walls. The invention also contemplates the provision of 10 means by which the condensate carried by the steam will be caused to pass out from the nozzle casing to prevent its interference with the introduction of live and relatively dry steam against the inner faces of the can walls.

In the preferred form of the invention shown in the accompanying drawing, Fig. 1 is a vertical sectional view of a steam nozzle made in accordance with this invention, and 20 Fig. 2 is a plan view of the same.

The nozzle forming the subject-matter of this invention is usually inserted within the can to be subjected to the action of steam to kill any deleterious microorganisms adhering thereto. The nozzle is provided with a central perforated pipe 3, the top or upper end of which is closed by a threaded cap 4. The pipe 3 is located in the bottom of a cylindrical shell or casing 5 which is longer and of 30 greater diameter than the pipe 3 and extends well up beyond the upper end of the pipe 3. The casing 5 is open at its upper end and closed at its lower end, with the exception of several small openings or drain holes 6 there- 35 in. The casing 5 is supported at its lower end by brackets 7 which are bolted at 8 to a pair of spaced supporting bars 9.

The center of the bottom of the shell or casing 5 is pierced to receive the lower end of the pipe 3 which is secured to the upper end of a steam-supply pipe 10. The pipe 10 is provided with a suitable valve, not shown, and when the valve is opened the steam rushes up into the perforated pipe 3, carrying with 50 it any condensate which has gathered in the

steam-supply pipe 10 or other pipes in the steam-supply system to which the pipe 10 may be connected. To prevent this condensate from being directed against the inner surfaces of the can and thereby interfere with the sterilizing action of the steam and make it harder later to dry the can, I provide the 55 perforated pipe with the cap 4 which compels the steam to leave the pipe 3 laterally through the relatively small apertures 11 60 therein, and pass out of the casing 5 at its open upper end. During the steaming of the interior surfaces of the can, the nozzle will, of course, be inserted up in the can. The condensate carried by the steam will impinge 65 against the inner walls of the casing 5 opposite the apertures 11 and will fall down onto the bottom of the casing and will run out through the holes 6 therein. Consequently only steam freed from condensate will be 70 driven against the inner surfaces of the can and it will therefore be understood that a very effective sterilizing action will be obtained. The drip from the bottom of the casing 5 may fall into a suitable receptacle located 75 beneath the nozzle or on the floor.

What I claim is:—

1. Means for steaming and sterilizing the inner surfaces of a hollow receptacle by directing substantially dry steam thereagainst comprising a nozzle including an upright perforated pipe cylindrical throughout its length and closed at its upper end, and an upright casing cylindrical throughout its length surrounding the perforated pipe in 80 spaced relation thereto, the upper end of the casing being unobstructedly open and the lower end of the casing being closed by a bottom through which the pipe projects upwardly into the casing, the bottom of the 85 casing having drain apertures therein and the perforations in the pipe extending from the bottom wall of the casing to the upper end of the pipe.

2. Means for steaming and sterilizing the 95 inner surfaces of a hollow receptacle by directing substantially dry steam thereagainst comprising a nozzle including an upright perforated pipe cylindrical throughout its length and closed at its upper end, and an 100

upright casing cylindrical throughout its length surrounding the perforated pipe in spaced relation thereto, the upper end of the casing being unobstructedly open and the lower end of the casing being closed by a bottom through which the pipe projects upwardly into the casing, the bottom of the casing having drain apertures therein and the perforations in the pipe extending from the bottom wall of the casing to the upper end of the pipe, and the casing being substantially twice the length of the pipe whereby entrained globules carried upwardly by the steam will impinge the side wall of the casing for deposit thereon.

JOHN M. McCLATCHIE.
